UNITED STATES PATENT OFFICE

JAMES E. GOODWIN, OF CEDAR BLUFF, VIRGINIA

AUTOMATIC FIRE ALARM

Application filed January 31, 1929. Serial No. 336,616.

This invention aims to provide a novel temperature-controlled switch mechanism whereby upon a rise of temperature, one circuit may be opened and another circuit 5 be closed, the structure being of peculiar utility in connection with fire alarm systems and the like.

It is within the province of the disclosure to improve generally and to enhance the 10 utility of devices of that type to which the invention appertains.

With the above and other objects in view, which will appear as the description proceeds, the invention resides in the combination and arrangement of parts and in the 15 details of construction hereinafter described and claimed, it being understood that, within the scope of what is claimed, changes in the precise embodiment of the invention 20 shown can be made without departing from the spirit of the invention.

In the accompanying drawings:—

Figure 1 shows in side elevation, a device 25 constructed in accordance with the invention;

Figure 2 is a longitudinal section where- 30 in some parts appear in elevation;

Figure 3 is a horizontal section on the line 3—3 of Figure 2;

Figure 4 is a bottom plan;

Figure 5 is an end elevation;

Figure 6 is a cross section on the line 6—6 of Figure 2;

Figure 7 is a longitudinal section similar 35 to Figure 2, but showing the parts as they will appear after the fuse has been melted out.

The device forming the subject matter of this application comprises what may be 40 designated under the general name of a frame, marked, as a whole, by the numeral 1. The frame 1 is made of porcelain or other insulating material, and includes a plate-like base 2, and a hollow body 3 de- 45 pending from the base 2, the base 2 being supplied in its lower surface with a depression 4 wherein the body 3 is received.

The body 3 is provided with a longitudi- 50 nal chamber 5 which, as shown in Figure 3 and in Figure 6, is somewhat restricted in

width. The chamber 5 is provided at one end with an enlarged circular extension 6 (Figure 3) which opens downwardly through the lower surface of the body 3 (Figure 2). The chamber 5 is provided at its opposite end with an enlarged circular extension 8 (Figure 3) which is not quite so large in diameter as the extension 6. It will be seen from Figure 2 that the extension 8 is not prolonged through the 55 lower surface of the body 3. The body is equipped with transverse recesses 10 located on opposite sides of the chamber 5. Referring to Figure 7, for instance, it can be plainly seen that the recesses 10 are not so 60 deep as the chamber 5.

By means of securing elements 11, mounted in holes 12, the body 3 is held on the base 2 detachably, and the securing elements 65 may be bolts.

An angle bracket 14 is provided and is supplied in its depending arm with an opening 15. A securing element 16a connects the bracket 14 with the body 3, at one end of the body. Comparing Figures 1 and 5, the reader will note that there is a binding member 16 on the exposed portion of the bracket 14, and this binding member holds the conductor 17, the conductor 17 being extended through a hole 18 in the frame 1.

At that end of the body 3 which is remote 70 from the angle bracket 14, there is another angle bracket which is marked by the numeral 19. A securing member 20, such as a screw, holds the angle bracket 19 on the 75 body 3. The angle bracket 19 carries a connecting screw 21 that retains the conductor 22, the conductor being extended through a hole 23 in the support 1, Figure 4 being referred to at this point. An angular arm 90 24, having some resiliency, is connected by a securing element 25 to the bracket 19, as shown in Figure 2, and the arm may be considered to be a part of the bracket. The arm 24 terminates in a reduced finger 26 95 (Figure 4). At 29 there is shown a link which is made of metal, like the arm 24 and the angle bracket 19. The link 29 is supplied at its inner end with a projection 32 100 which gives a good anchorage (Figure 2)

for a mass of fusible material 27 joining the reduced end 28 of the link 29 to the finger 26 of the arm 24 on the bracket 19, the parts 28 and 26 being overlapped on each other.

5 The outer end of the link 29 is fashioned into a hook including a bend 30 and a support 31 projecting backwardly through the opening 15 in the angle bracket 14. The part 31 of the link 29 is called a support 10 because it up-holds a weight 33 that is vertically slidable in the extension 6 of the chamber 5 in the body 3, Figures 2 and 7 being compared. The weight 33 is equipped at its lower end with an outstanding rim 34 15 which, cooperating with the lower surface of the body 3, limits the upward movement of the weight 33 if the weight 33 is shoved upwardly too far whilst the body 3 is detached from the base 2.

20 The weight 33 is of frusto-conical form and has a slot 35 in its upper end. A pivot element 36 is mounted in the upper end of the weight 33 and extends across the slot 35. The pivot element 36 forms a connection 25 between the weight 33 and a rigid lever 37 which is movable in the longitudinal chamber 5 of the body 3. In that end of the lever 37 which is remote from the pivot element 36, there is an opening 38 through which 30 extends a fulcrum pin 39. The opening 38 preferably is a good deal larger in diameter than the pin 39 so that the lever can have a somewhat loose fulcrum on the pin, a free and easy movement of the lever thus being assured. The ends of the fulcrum pin 39 35 are received in the seats 9, as shown in Figure 3, the construction being such that the fulcrum pin and the lever can be easily removed when the body 3 is detached from 40 the base 2.

A pair of metal contact members 40 are located in the transverse recesses 10 and have downwardly extended, converging, resilient tongues 41 that project (Figure 6) into the 45 longitudinal chamber 5 and extend beneath the switch lever 37. On top of the contact members 40 are placed metal washer blocks 42. Securing devices 43 (Figure 6) pass through the blocks 42, the contact members 50 40, and through the body 3. At their lower ends, the securing devices 43 are threaded into anchor plates 44 (Figure 6 and 4) seated in recesses on the lower surface of the body 3. The anchor plates 44 carry binding screws 45 holding conductors 46 which are extended upwardly through holes 47 in the frame 1.

When the fusible material 27 is in place, as shown in Figure 2, there is provided a 60 closed circuit including the conductor 17, the angle bracket 14, the link 29, the fusible material 27, the arm 24, the bracket 19, and the conductor 22. Although the weight 33 rests on the finger 31 of the link 32, as 65 shown in Figure 2, this closed circuit is not

shorted through the weight 33 and the lever 37, because the body 3 and the base 2 are made of insulating material, and because the lever 37 (Fig. 6) does not touch the tongues 41 when the parts are arranged as shown in Figures 2 and 6. 70

The device includes a normally open circuit embodying the conductors 46, the anchor plates 44, the securing devices 43, the conducting members 40, and the tongues 41 of Figure 6. The circuit described is an open circuit, because, with the parts arranged as shown in Figures 6 and 2, the lever 37 does not touch the tongues 41. 75

When the fusible material 27 melts, the link 29 swings down into the position of Figure 7, the parts 28 and 26 are separated and the support hereinbefore described as a closed circuit, is opened. 80

When the parts assume the positions of 85 Figure 7, the support 31 no longer carries the weight 33 and the weight 33 moves downward by gravity.

When the weight 33 moves downward, as aforesaid, the lever 37 swings on the fulcrum pin 39 and engages the tongues 41 90 of Figure 6. The circuit hereinbefore described as an open circuit, now is closed.

In order to restore the parts from the position of Figure 7 to the original position of 95 Figure 2, it is necessary merely to swing up the link 29 and fasten it to the part 26 of the arm 24 by means of the fusible material shown at 27. The support 31 raises the weight 33 and tilts the lever 37 on its fulcrum 39 until the lever is in the position of Figure 6 and out of contact with the tongues 31. 100

What is claimed is:—

1. In a thermal switch, the combination of 105 a frame, a lever fulcrumed on the frame for vertical downward swinging movement, a depending weight mounted on the lever, and constituting means for swinging the lever downwardly, a contact member on the frame 110 and out of electrical engagement with the lever when the lever is raised, the lever engaging the contact member when the lever swings downwardly, responsive to the weight, a link embodying a fusible portion, the weight resting directly on a part of the link, to support the weight, hold the lever raised, and keep the lever out of electrical engagement with the contact member, and means for mounting the link on the frame at 115 spaced points on opposite sides of the weight, both of said means being spaced from the lever and being independent thereof. 120

2. In a thermal switch, the combination of 125 a frame, a contact member on the frame, a lever fulcrumed on the frame, a weight carried by the lever, a bracket on the frame, a link having a hook engaged pivotally through the bracket, the end of the hook engaging the weight to raise the weight and 130

hold the lever out of engagement with the contact member, and fusible means cooperating with the opposite end of the link to hold it in weight-engaging position.

3. In a thermal switch, a body provided
5 in its upper surface with a chamber, there
being oppositely disposed seats in the body,
the seats being in communication with the
chamber, and opening through the upper
10 surface of the body, the seats being at one
end of the chamber and the body being pro-
vided with an opening disposed at the oppo-
site end of the chamber, the opening extend-
ing through the lower surface of the body,
15 a base secured to the top of the body, a ful-
crum pin having its ends mounted in the
seats and retained therein by the base, a
weight slideable in the opening, a lever pivot-
ed to the weight, the lever being fulcrumed
20 on the pin and being mounted in the cham-
ber, a contact member on the body and
wherewith the lever engages when the
weight descends, and mechanism for holding
the weight elevated, said mechanism com-
25 prising a fusible member.

In testimony that I claim the foregoing
as my own, I have hereto affixed my signa-
ture.

JAMES E. GOODWIN.
